UNITED STATES PATENT OFFICE

MORRIS MOREINES, OF NEWARK, NEW JERSEY

SAFETY SWITCH CABINET

Application filed June 16, 1931. Serial No. 544,723.

This invention relates to enclosed safety switch cabinets, and more particularly to a cabinet of this nature having a cover and means associated therewith for holding such cover positively locked so long as the switch remains closed.

The invention is closely related to that disclosed in my prior co-pending application S. N. 525,072, filed March 15, 1931. The general objects of the present invention are therefore similar to those set forth in said prior application.

A further and special object of the present invention, however, is to provide several forms of improved locking means for the door of a switch cabinet of the type referred to, whereby the door is maintained locked so long as the switch is closed, and the switch-operating mechanism is automatically held in inoperative or "off" position so long as the door is open.

More specifically, the invention contemplates the provision of a sliding locking member mounted inside the cabinet, means whereby this locking member, and the switch mechanism to which it is connected, are held against movement when the door is open, and means whereby said member is shifted by the closing movement of the switch, after the door has been shut, into a position in which it positively locks the door.

With the above and other objects in view, the invention consists in the various constructions, combinations and arrangements of parts hereinafter described and claimed, and illustrated, by way of example, in the accompanying drawings, in which:

Fig. 1 is a plan view of a complete cabinet showing the door in open position and partially broken away, and having the first form of locking mechanism installed therein;

Fig. 2 is a longitudinal section substantially on the line 2-2 of Fig. 1 with the door in closed position;

Fig. 3 is an enlarged fragmentary view of the inner right wall of the cabinet showing the door locking means, the door being shown partially open and the switch handle locked in "off" position;

Fig. 4 is a transverse section on the line

4-4 of Fig. 3, looking in the direction of the arrows;

Fig. 5 is a fragmentary view similar to Fig. 3, but showing the door closed and locked;

Fig. 6 is a fragmentary plan view of a modified form of locking mechanism;

Fig. 7 is a side elevation thereof, looking from the inside of the cabinet, parts being in section;

Fig. 8 is a transverse section on the line 8-8 of Fig. 7;

Fig. 9 is a fragmentary sectional elevation similar to Fig. 7 but showing the door partially open and the switch operating mechanism locked against movement;

Fig. 10 is a plan view of a further modified construction of door locking mechanism;

Fig. 11 is a side elevation thereof, looking from the inside of the cabinet, parts being in section, and the door being shown as locked;

Fig. 12 is a transverse section on the line 12-12 of Fig. 11, looking in the direction of the arrows;

Fig. 13 is a fragmentary sectional elevation similar to Fig. 11, but showing the door partially open and the switch operating mechanism locked in "off" position;

Fig. 14 is a plan view similar to Fig. 6, but showing a still further modified arrangement of locking mechanism;

Fig. 15 is a side elevation thereof, looking from the inside of the cabinet, the cover being shown in section and in locked position;

Fig. 16 is a transverse section on the line 16-16 of Fig. 15, looking in the direction of the arrows;

Fig. 17 is a fragmentary sectional elevation similar to Fig. 15, but showing the door in partially opened position and the switch operating mechanism locked against movement;

Fig. 18 is a fragmentary plan view of a further modified form of the invention, having a different type of actuating mechanism for the locking means shown in Figs. 10 to 13;

Fig. 19 is a side elevation of the same, looking from the inside of the cabinet, the cover

being shown in section and in locked position;

Fig. 20 is a transverse section on the line 20—20 of Fig. 19, looking in the direction of 5 the arrows; and

Fig. 21 is a side elevation similar to Fig. 19, but showing a still further modified form of locking mechanism actuating means.

Referring to the drawings in detail, and 10 more particularly first to Figs. 1 to 5 inclusive, 10 designates the cabinet which may conveniently be formed of sheet metal.

As in my said prior application, I have 15 shown this cabinet as provided with two separate doors 11 and 15, the first covering the switch and the second the usual fuses, the door 11 being mounted on the cabinet by means of hinges 12 and the door 15 being mounted on hinges 16.

20 Although I have thus illustrated a cabinet having two separate doors, it will be understood that the present invention is equally applicable to cabinets having but a single door.

25 The switch is indicated at 14 and is shown as of the usual double pole knife blade type, the blades being pivoted at 20^a to clips 19, and being adapted to engage other clips 20 when in closed position.

30 Pairs of fuse clips 17 and 27 are provided to receive the usual fuses 26, the clips 27 being connected by bars 28 with the switch clips 19, all of the fuse and switch clips being preferably mounted upon a panel 18 of insulating material, such as slate or the like.

The switch blades 14 are bridged by a bar 21 of insulating material and secured to this bar is a bracket 21^a having an opening 21^b through which extends a U-shaped switch 40 operating rod 22 journaled in the side walls of the cabinet as at 23 and extending outside of the cabinet, as indicated at 24, the extended end being bent upwardly to form a handle, as shown at 25. A spring 21^c preferably connects the rod 22 with the bracket 21^a so as to produce a snap action when the switch is operated, and thus prevent objectionable arcing.

As in my prior co-pending application, the 50 cabinet is illustrated as provided with two doors 11 and 15 which are constructed to interlock in such a way that the switch door 11 can not be opened while the fuse door 15 is locked closed. This is effected by securing a strip 29 to the inner edge of the door 11, as by welding, which strip overlies the adjacent edge 30 of the door 15. My improved locking mechanism described in this application is shown as applied to the fuse door 15, and 55 since, as above mentioned, this door is interlocked with the switch door, the result of the arrangement is that both doors are locked whenever the fuse door is locked, and to this extent the two doors are the equivalent of a 60 single door. So far as concerns the improved

locking mechanism forming the subject of the present invention, therefore, it is immaterial whether an interlocked pair of doors or a single door is employed.

Secured to the inside of the door 15 is a 70 Z-shaped locking bracket 31, and end 32 of which, when the door is closed, is adapted to enter the transverse portion 33 of an L-shaped slot 34 formed in a sliding locking member 35 mounted upon the inner wall of 75 the cabinet. As shown, this sliding member 35 may be of channel section and is provided with longitudinal slots 35^a which engage with projections 35^b carried by a guide plate 35^c secured to the wall of the cabinet and spaced therefrom sufficiently to receive one flange of the channel shaped sliding member 35. 80

85 A resilient latch 36, preferably in the form of a leaf spring, is secured at one end to a bracket 46 supported upon the guide plate 35^c in such a manner that it is free and projects upwardly into the slot 33—34, as clearly shown in Fig. 1, and thus prevents the sliding member 35 from being shifted, so long as the door 15 is open. When, however, 90 the door 15 is closed, the end 32 of the bracket 31 engages and depresses the upwardly projecting end of the latch 36 into the position shown in Fig. 5, so that this latch no longer engages the slot in the sliding member 35 and 95 such member is free to be shifted. When the sliding member is then shifted longitudinally toward the center of the cabinet, the end 32 of the bracket 31 engages under that portion of the sliding member 35 adjacent 100 the slot 34 and the door 15 is thereby locked in closed position.

105 The sliding locking member 35 is shifted by the switch operating rod 22 which engages between the legs of a forked bracket 45 secured to the sliding member 35, as clearly shown in Figs. 3 and 4. Thus, when the rod 22 is swung upwardly, as viewed in Fig. 1, the sliding member 35 is shifted in the same direction and the door 15, having been previously shut, is locked in closed position.

110 In addition to the automatic locking means controlled by the switch operating mechanism, as above described, I preferably provide other locking means comprising resilient locking plates 39 and 40 which project upwardly from the side wall of the cabinet and are received in slots 37 and 38 formed in the doors. The locking plates 39 and 40 carry laterally projecting nibs 43 and 44, which, when the doors are closed, engage the outer surfaces of the doors. These resilient locking plates can be manually released by pressing them outwardly. If desired, they 115 may be provided with openings 41 and 42 through which padlocks may be passed for preventing access to the cabinet when desired.

120 In the modified construction shown in Figs. 6 to 9 inclusive, I have illustrated a 125

- slightly different form of sliding locking member 47 which is angular in cross section. This is slidably supported on a Z-shaped bracket 49 by means of rivets 48 or 5 the like which work freely in slots 47^a formed in the downwardly extending flange of the sliding member. The supporting bracket 49 has its other flange 49^a secured to the wall of the cabinet as by spot welding.
- 10 The supporting bracket 49 is formed with a slot 50, and the sliding member 47 is provided with a notch 51 which are adapted to be brought into registry when it is desired to unlock the door. Secured to the door or 15 cover 15 is an angle bracket 52 having a notch 53 formed in the side of its depending portion, and when the notch 51 is in registry with the slot 50, the end of this angle bracket may enter the slot and notch freely. When, 20 however, after the bracket 52 has entered the slot 50, the sliding locking member is shifted to a position such as that shown in Figs. 6 and 7, its edge then engaging in the notch 53 and thus locking the door in closed position.
- When, however, the notch 51 registers with the slot 50 and the bracket 52 is withdrawn therefrom by opening the door, a spring pressed latch 54 enters the notch 51 from 30 below and thus locks the sliding member against movement. This latch 54 is shown as secured to the end of a leaf spring 55 supported on the bracket 49.
- In the present construction, the switch operating rod 22 is operatively connected with the sliding member 47 by means of a link 56 connecting such member with a lever 57 secured to an angle bracket 58 having a notch 59 therein to receive the rod 22, as clearly 40 shown in Figs. 6 and 7, and lever 57 and bracket 58 being mounted upon the rod 22 itself adjacent the wall of the cabinet.
- In Figs. 10 to 13 inclusive, I have illustrated a further somewhat modified construction of locking mechanism which may be employed. In this modification, I have illustrated the switch operating mechanism as comprising a handle 60 terminating in a truncheon 61 which is journaled in the wall 50 of the cabinet and in which one end 62^a of the switch operating rod 62 is secured by means of a set screw 61^a. The rod 62 engages between the legs of a forked bracket 63 secured to the sliding member 64 which 55 is of angle section. It is slidably supported on the cabinet wall by means of rivets 66 engaging in slots 65 formed in the vertical flange. The horizontal flange is cut away at one point to form a square shouldered notch 67 and also set into and projecting down below this horizontal flange adjacent the notch is a lug 68. This is adapted to engage at times with the head 69 of a locking pin 69^a mounted for vertical reciprocation 60 in a fixed bracket 70 secured to the cabinet
- wall. The pin 69^a has a collar or shoulder 69^b, and between this and the lower arm of the bracket 70 is interposed a helical spring 69^c which surrounds the pin and normally urges it upwardly, such upward movement being limited by a cotter pin 69^d extending through the lower end of the pin 69^a.
- Depending from the inside of the door or cover 15 is an angle bracket 71 having a notch 72 formed in the side of the vertical portion thereof, such notch being adapted to receive the horizontal flange of the sliding locking member 64. When such flange is engaged in the notch 72, as shown in Figs. 10 and 11, the door 15 is locked and the end of the bracket 71 depresses the pin 69^a, as shown in Fig. 11. When, however, the notch 67 is brought into a position opposite the bracket 71, then this bracket may be moved upwardly and the door opened. When, however, the sliding member 64 is shifted to such a position as to bring the notch 67 opposite the bracket 71, the lug 68 is carried to the right hand side of the pin 69^a, as viewed in Figs. 10 and 11, so that when the bracket 71 is withdrawn the pin rises, under the influence of the spring 69^c, and interposes its head in the path of movement of the lug 68, as shown in Fig. 13, thus locking the sliding member against movement toward the left. Preferably, the right hand side of the lug 68 is beveled, as shown, so that it will snap over the head 69 of the pin if it is moved toward the right when the pin is in its upper position.
- In Figs. 14 to 17 inclusive, I have illustrated a still further modified arrangement of locking mechanism. In this construction, the sliding member is indicated at 73 and is of angle section, slidably supported by means of slots 75 working over rivets 76 set into the wall of the cabinet. As in the previously described modification, the vertical flange of the sliding member is provided both with a notch and with a depending lug, the former being indicated at 74 and the latter at 77.
- An angle shaped latch 78 is disposed just below the sliding member and is mounted for vertical reciprocation in a fixed bracket 80 secured to the wall of the cabinet and having a pair of spaced arms, between the lowermost of which and a shoulder 78^a on the latch is confined a helical spring 79 which urges the latch upwardly, such upward movement being limited by a cotter pin 79^a in the lower end of the latch. The horizontal portion of the latch 78 is disposed immediately beneath the end of an angle bracket 81 carried by the cover or door 15 and provided in its edge with a notch 82 adapted to receive the edge of the sliding member 73. The operation of the latch, notch and lug shown in these figures is substantially the same as that illustrated in Figs. 10 to 13, inclusive.
- A slightly different switch operating connection is, however, illustrated. A bracket 130

83 is secured to the sliding member 73 and depends therefrom. It is provided with a vertical slot 84 in which works a pin 85 carried by a lever 86 having a circular opening 87 and a pair of spaced pins 88 adjacent such opening. The lever 86 is adapted to fit over a trunnion 89 journaled in the wall of the cabinet 10 and integral with a handle 90 operated from the outside of the cabinet. 10 One end 91a of a switch operating rod 91 is passed transversely through the trunnion 89 and extends slightly beyond said trunnion, being secured therein by means of a set screw 89a. The extended end 91a of the operating rod 91 engages between the pins 88 and thus causes the lever 86 to be rocked back and forth, as clearly shown in Fig. 15.

In Figs. 18 to 20, inclusive, I have illustrated a still further modified arrangement 20 of locking mechanism. In this construction, a sliding member 92 is provided with a pair of slots 93 fitting around a pair of spaced brackets 94, welded or otherwise secured to the wall of the cabinet 10. The sliding member 92 is provided at its right-hand end, as viewed in Figs. 18 and 19 with a horizontal flange 95 having a notch 96 cut therein and adjacent said notch is a depending lug 97 having a beveled shank, said construction 25 being identical with that of the third form of the invention shown in Fig. 13. The sliding member 92 is provided on its left-hand end with an offset depending flange 97 having secured thereto a vertical toothed rack 98 which is adapted to engage an oscillating vertical segment gear 99 located beneath it. The segment gear 99 is adapted to fit over a horizontal trunnion 100 journaled in the wall 30 of the cabinet 10 and integral with a handle 101 operated from the outside of said cabinet.

A horizontal bifurcated lug 102 is formed at the lower end of the segment gear 99 and engages the lower vertical end 103 of a switch operating rod 104, said vertical end 103 being 45 secured within the trunnion 100 by means of a set screw 105. Thus, it will be clear that by operating the handle 101, the segment gear will be caused to oscillate, which in turn will reciprocate the sliding member 92 and perform the same functions as stated in the 50 previous described forms.

Fig. 21 shows a still further modified form of actuating means for the slidable locking member illustrated in Figs. 10 to 13 and 18 55 to 20. In this form, the offset depending flange 97 of the sliding member 92 has a depending cog 105 adapted to mesh between a pair of upstanding cogs 106 formed on an oscillating member 107 journaled upon the trunnion 100 of the handle 101. The lower 60 end of said oscillating member 107 has formed thereon a bifurcated flange 108 which functions similarly to the flange 103 on the segment gear 99, shown in Figs. 18 to 20.

65 It will thus be seen that all of the various

modifications which I have illustrated and described operate upon the same general principle. In all of them, there is a sliding locking member, and in all of them there is a latch which, when the door is open, engages the sliding member and holds it against movement, thus preventing the switch from being closed. Also, in all of the modifications, the sliding member, when the switch is closed, engages a bracket on the door or 70 cover and thus maintains the same locked.

Having thus fully described the invention, what is claimed as new and for which it is desired to secure Letters Patent, is:

1. In an enclosed safety switch, a cabinet having a switch located therein, a switch-operating member having a portion extending outside of said cabinet, a hinged cover for closing said cabinet, said cover having a depending hook member adjacent its free edge, an angle bar slidably mounted on the side of said cabinet, said sliding bar having an aperture adapted to aline with said hook member when the switch is fully open, said bar serving to fit into said hook member to lock said cover closed when said aperture is out of alinement with said hook, said switch-operating member having an operative connection with said sliding bar to move said bar into cover-locking position when the switch is closed, and a spring-locking device carried by said cabinet for locking said switch open as long as said cover remains open.

2. In an enclosed safety switch, a cabinet having a switch located therein, a switch-operating member having a portion extending outside of said cabinet, a hinged cover for closing said cabinet, said cover having a depending hook member adjacent its free edge, an angle bar slidably mounted on the side of said cabinet, said sliding bar having an aperture adapted to aline with said hook member when the switch is fully open, said bar serving to fit into said hook member to lock said cover closed when said aperture is out of alinement with said hook, said switch-operating member having an operative connection with said sliding bar to move said bar into cover-locking position when the switch is closed, and a spring-locking device carried by said cabinet, said spring-locking device extending into said aperture to lock said switch open when the cover is open.

3. In an enclosed safety switch, a cabinet having a hinged knife blade switch located therein, a switch-operating member having a handle portion extending outside of said cabinet, a hinged cover for closing said cabinet, said cover having a depending hook member adjacent its free edge, an angle bar slidably mounted on the side of said cabinet, said sliding bar having an aperture adapted to aline with said hook member when the switch is fully open, said bar serving to fit into said hook member to lock said cover 120

- closed when said aperture is out of alinement with said hook, said switch-operating member having an operative connection with said sliding bar to move said bar into cover-locking position when the switch is closed, and a spring-locking device carried by said cabinet for locking said switch open as long as said cover remains open.
4. In an enclosed safety switch, a cabinet having a switch located therein, a switch-operating member having a portion extending outside of said cabinet, a hinged cover for closing said cabinet, said cover having a depending Z-shaped hook member adjacent its free edge, a channel-shaped bar slidably mounted on the side of said cabinet, said sliding bar having an aperture adapted to aline with said hook member when the switch is fully open, said bar serving to fit into said hook member to lock said cover closed when said aperture is out of alinement with said hook, said switch-operating member having an operative connection with said sliding bar to move said bar into cover-locking position when the switch is closed, and a spring-locking arm carried by said cabinet for locking said switch open as long as said cover remains open, said spring-locking arm being horizontal and having an upturned extremity in alinement with said hook member.
5. In an enclosed safety switch, a cabinet having a switch located therein, a switch-operating member having a portion extending outside of said cabinet, a hinged cover for closing said cabinet, said cover having a depending hook member adjacent its free edge, a channel bar slidably mounted on the side of said cabinet, said sliding bar having an aperture adapted to aline with said hook member when the switch is fully open, said bar serving to fit into said hook member to lock said cover closed when said aperture is out of alinement with said hook, said switch-operating member having an operative connection with said sliding bar to move said bar into cover-locking position when the switch is closed, and a spring-locking arm carried by said cabinet for locking said switch open as long as said cover remains open.
6. In an enclosed safety switch, a cabinet having a switch located therein, a switch-operating member having a portion extending outside of said cabinet, a hinged cover for closing said cabinet, said cover having a depending hook member adjacent its free edge, a channel bar slidably mounted on the side of said cabinet, said sliding bar having an aperture adapted to aline with said hook member when the switch is fully open, said bar serving to fit into said hook member to lock said cover closed when said aperture is out of alinement with said hook, said switch-operating member having an operative connection with said sliding bar to move said bar into cover locking position when the switch is closed, and a spring-locking plunger carried by said cabinet for locking said switch open as long as said cover remains open.
7. In an enclosed safety switch, a cabinet having a switch located therein, a switch-operating member having a portion extending outside of said cabinet, a hinged cover for closing said cabinet, said cover having a depending hook member adjacent its free edge, an angle bar slidably mounted on the side of said cabinet, said sliding bar having an aperture adapted to aline with said hook member when the switch is fully open, said bar serving to fit into said hook member to lock said cover closed when said aperture is out of alinement with said hook, said switch-operating member having an operative connection with said sliding bar to move said bar into cover-locking position when the switch is closed, and a spring-locking arm carried by said cabinet for locking said switch open as long as said cover remains open, said spring-locking arm being horizontal and having an upturned extremity in alinement with said hook member.
8. In an enclosed safety switch, a cabinet having a switch located therein, a switch-operating member having a portion extending outside of said cabinet, a hinged cover for closing said cabinet, said cover having a depending hook member adjacent its free edge, an angle bar slidably mounted on the side of said cabinet, said sliding bar having an aperture adapted to aline with said hook member when the switch is fully open, said bar serving to fit into said hook member to lock said cover closed when said aperture is out of alinement with said hook, said switch-operating member having an operative connection with said sliding bar to move said bar into cover-locking position when the switch is closed, and a spring-locking device carried by said cabinet for locking said switch open as long as said cover remains open, said cabinet having a pair of auxiliary vertical locking strips having nibs, and said cover having a pair of slots in alinement with said strips.
9. In an enclosed safety switch, a cabinet having a switch located therein, a switch-operating member having a portion extending outside of said cabinet, a hinged cover for closing said cabinet, said cover having a depending hook member adjacent its free edge, an angle bar slidably mounted on the side of said cabinet, said sliding bar having an aperture adapted to aline with said hook member when the switch is fully open, said bar serving to fit into said hook member to lock said cover closed when said aperture is out of alinement with said hook, said switch-operating member having an operative connection with said sliding bar to move said bar into cover-locking position when the switch is closed, and a spring-locking device carried by said cabinet for locking said switch open as long as said cover remains open, said bar

having a pin-and-slot connection with said cabinet to limit its sliding movement in each direction.

10. In an enclosed safety switch, a cabinet having a switch located therein, a switch-operating member having a portion extending outside of said cabinet, a hinged cover for closing said cabinet, said cover having a depending hook member adjacent its free edge, an angle bar slidably mounted on the side of said cabinet, said sliding bar having an aperture adapted to aline with said hook member when the switch is fully open, said bar serving to fit into said hook member to lock said cover closed when said aperture is out of alinement with said hook, said switch operating member having an operative connection with said sliding bar to move said bar into cover-locking position when the switch is closed, and a spring-locking plunger carried by said cabinet for locking said switch open as long as said cover remains open, said bar having a lug on its under side to engage with said plunger and lock said bar against sliding movement when the cover is open.

11. In an enclosed safety switch, a cabinet having a switch located therein, a switch-operating member having a portion extending outside of said cabinet, a hinged cover for closing said cabinet, said cover having a depending hook member adjacent its free edge, an angle bar slidably mounted on the side of said cabinet, said sliding bar having an aperture adapted to aline with said hook member when the switch is fully open, said bar serving to fit into said hook member to lock said cover closed when said aperture is out of alinement with said hook, said switch-operating member having an operative connection with said sliding bar to move said bar into cover-locking position when the switch is closed, and a spring-locking device carried by said cabinet for locking said switch open as long as said cover remains open, said bar having a depending yoke member for operative engagement with said switch operating member.

12. In an enclosed safety switch, a cabinet having a switch located therein, a switch-operating member having a portion extending outside of said cabinet, a hinged cover for closing said cabinet, said cover having a depending hook member adjacent its free edge, an angle bar slidably mounted on the side of said cabinet, said sliding bar having an aperture adapted to aline with said hook member when the switch is fully open, said bar serving to fit into said hook member to lock said cover closed when said aperture is out of alinement with said hook, said switch-operating member having an operative connection with said sliding bar to move said bar into cover-locking position when the switch is closed, and a spring-locking device carried

by said cabinet for locking said switch open as long as said cover remains open, said bar having a depending slotted bracket for operative engagement with the crank arm of a rotary switch operating member.

13. In an enclosed safety switch, a cabinet having a switch located therein, an oscillatable switch-operating member having a handle portion extending outside said cabinet, a cover for closing said cabinet, a sliding angle bar carried by said cabinet and having detachable interlocking engagement with said cover, said sliding bar having a toothed rack, and a gear connected to said switch-operating member for meshing with said rack to actuate said sliding bar.

14. In an enclosed safety switch, a cabinet having a switch located therein, an oscillatable switch-operating member having a handle portion extending outside said cabinet, a cover for closing said cabinet, a sliding angle bar carried by said cabinet and having detachable interlocking engagement with said cover, said sliding bar having a depending cog, and a bifurcated member embracing said cog, said bifurcated member being connected to said switch-operating member whereby oscillation thereof will slide said bar.

In testimony whereof, I have affixed my signature to this specification.
